UNITED STATES PATENT OFFICE.

PETER DE MATTIA, OF PASSAIC, NEW JERSEY, ASSIGNOR TO DE MATTA BROS., OF GARFIELD, NEW JERSEY, A CORPORATION OF NEW JERSEY.

COLLAPSIBLE CORE.

Application filed June 21, 1923. Serial No. 646,891.

To all whom it may concern:

Be it known that I, PETER DE MATTIA, a citizen of the United States, and a resident of Passaic, in the county of Passaic and State of New Jersey, have invented certain new and useful Improvements in Collapsible Cores, of which the following is a full, clear, and exact description.

The present invention relates to collapsible cores used in the manufacture of casings or shoes for pneumatic tires. Such cores are made up of a plurality of segmental core sections which, when arranged to constitute a complete annulus, are all in the same plane, and the sections are supported by means which either permit or cause movement of the sections, or some of them, so that the core may be collapsed as required. In some instances the core sections not only are movable radially to complete or collapse the core, but some of them are movable into and out of the plane of the core when the sections are assembled for use, this movement greatly facilitating the collapsing of the core by moving certain sections above or below such plane and out of the path of movement of other sections.

The present invention constitutes an improvement on the subject matter of my application, Serial No. 586,696, filed September 7, 1922, Patent No. 1,475,109.

The object of the present invention is to produce a collapsible core in which a plurality of segmental core sections are arranged to be moved into and out of the position of operative continuity and at the same time with relation to the plane of operative continuity, the movement of adjacent core sections with relation to the plane of operative continuity being in opposite directions, and whereby opposite pairs of core sections may be moved simultaneously, certain core sections being movable on curved lines.

A further object of the invention is to provide a collapsible core comprising a plurality of segmental sections in which one of the sections is movable in a curved path toward and from the position of operative continuity, and with relation to the plane of operative continuity, thus greatly assisting in the withdrawal of the core from the shoe or casing without unduly distorting the same.

The invention consists of a collapsible core comprising a plurality of segmental core sections with means for moving one of the said

sections into and out of a position of operative continuity and with relation to the plane of operative continuity in a curved path.

The invention further consists of the devices and combinations of devices which will be hereinafter set forth.

The invention is illustrated in the accompanying drawings, in which—

Fig. 1 shows a front elevation with the core sections extended and in the position of operative continuity and all of the sections in the same plane or the plane of operative continuity.

Fig. 2 shows a sectional view taken on the line 2—2 in Fig. 5, looking in the direction 70 of the arrow in that figure.

Fig. 3 is a sectional view taken on the line 3—3 in Fig. 1, looking in the direction of the arrow in that figure which crosses the line 3—3.

Fig. 4 is a sectional view taken on the line 4—4 in Fig. 3 looking in the direction of the arrow in that figure.

Fig. 5 is a sectional view taken on the line 5—5 in Fig. 1, looking in the direction 80 of the arrow at the bottom of Fig. 1.

Fig. 6 is an elevation showing the core collapsed.

Figs. 7 and 8 show details representing gearing which may be employed to insure simultaneous movement of one pair of core sections.

Similar reference characters will be employed throughout the specification and drawings to designate corresponding parts.

The core is made up of four segmental sections—1, 2, 3 and 4—divided upon lines 5, which extend tangentially and converge slightly from the inner to the outer circumference, thus producing relatively large core sections 3 and 4 and the relatively small core sections 1 and 2; the sections 1 and 2 being in the nature of key sections fitting between the sections 3 and 4 and movable with relation thereto, preliminary to the movement of the sections 3 and 4.

The sections 1 and 2 are each provided with a curved shank 6 which upon the inner surface is provided with worm teeth 7, and the shanks 6 have a sliding movement 105 in bearings 8 formed at the base of a casting 9, the shank 6 being retained in the bearings 8 by means of plates 10 secured to the casting 9 by screws 11 and covering the said bearings and the shanks 6, the 110

under surface of the plates 10 being curved to coincide with the curve of the shanks 6, thus the shanks 6 while freely movable in the bearings, are at all times properly supported and guided so that the core sections supported by the shanks 6 will be caused to move in curved lines corresponding to the arc of curvature of the shanks 6. The casting 9 is also provided with bearings 12 at or near the base thereof, in which are mounted to turn freely the lower ends of shafts 13, the said shafts 13 being also supported in bearings 14 positioned at the outer or upper end of the casting 9, and they are held in place by the nuts 15 received in sockets 16 at the base of the casting, and also by the worms 17 which are secured to the shafts 13 by means of collars 18 pinned to the said shafts by the dowels 19, the worms 17 being in mesh with the worm racks 7 of the shanks 6. The shafts 13 at their upper ends are provided with polygonal extensions 20 whereby they may be engaged by a suitable wrench and turned, and thus through the worm and worm gear connections move the shanks 6 and the core sections 1 and 2 connected to or carried thereby. As shown in Fig. 5, the shafts 13 are arranged to be turned independently, and thus one of the sections 1 or 2 may be moved independently of the other, but if it be desired that the sections be simultaneously moved, then the arrangement shown in Figs. 7 and 8 may be employed. This consists of a gear 21 fixedly secured to each of the polygonal extensions 20 of the shafts 13, the gears 21 meshing with an intermediate gear 22 mounted to loosely turn about the shaft 23 supported centrally between the shafts 13 and held in place by a collar 24 carried by the shaft 23. This arrangement is such that by fitting the key to either one of the polygonal extensions 20 and turning the shaft 13, to which the key is fitted, will result in the simultaneous rotation of the other shaft 13, and thus a simultaneous movement of the core sections 1 and 2 will be effected. As shown in dotted lines in Fig. 5, these core sections, by reason of the curved shank 6, have a movement in a curved line toward and from the position of operative continuity, and into and out of the plane of operative continuity.

The core sections 3 and 4 are provided with straight shanks 25 extending obliquely or inclined to the plane of operative continuity, and in a direction opposite to that at which the shanks 6 extend. The shafts 25 are fitted to have a free sliding movement in bearings 26 formed partially in the casting 9 and in oppositely diverging projections 27 extending from the forward end of the said casting, the shanks 25 being held therein by means of cover plates 28 fixed in position over the shanks and over the bearings 26 by means of screws 28. The bearings 14 for the shafts 13 are carried by these cover plates. The shanks 25 cross each other upon a line coincident with the axis of the casting 9, and upon the opposed inner faces they are provided with inclined rack teeth 29 engaging and meshing with a worm 30 mounted in a bearing 31 in the outer end of the casting 9 and held therein by a bushing 32 which engages a threaded recess in the outer end of the said casting. The worm 30 is provided with a polygonal extension 33 whereby it may be turned and thus impart to the shanks 25 movement in opposite directions in the bearings 26, a turning of the worm 30 in one direction causing the shanks 25 to draw the sections 3 and 4 towards each other in an oblique or inclined line, and a movement in the opposite direction results in a movement of the sections 3 and 4 outwardly on an inclined or oblique line, the result of this movement moving the core sections 3 and 4 not only with relation to the position of operative continuity but with relation to the plane of operative continuity. The core and the casting which supports the same, which is technically known as a "chuck" in this art, are intended to be mounted so that the core may be freely turned about a center coinciding with the axis of the casting, and for this purpose the casting is provided with a socket 34 whereby it may be supported upon a spindle carried by a jack or other support (not shown).

In operation, assuming that the parts are in the position shown in Fig. 1, wherein the core sections are not only in the position of operative continuity but also in the same plane or the plane of operative continuity, and that a tire shoe or casing has been built up thereon and is ready to be removed therefrom, the first operation is to remove the sections 1 and 2 from the core, and this may be accomplished either by moving them separately or simultaneously, such movement being accomplished by the turning of the shafts 13, thus through the worms 17 and the worm racks 7 drawing the core sections 1 and 2 inwardly and rearwardly on curved lines. Until the sections 1 and 2 have been withdrawn, it will of course be impossible to move the sections 3 and 4. Having withdrawn the sections 1 and 2, then by turning the worm 30 an inward and outward movement will be imparted to the sections 3 and 4. When moved to the maximum extent, the core sections will be approximately in the position shown in Fig. 6, wherein the sections 3 and 4 are

shown in advance of and overlapping the ends of the sections 1 and 2, shown partially in dotted lines. The movement of the core sections 3 and 4 carries with it the shoe 5 or casing which, when the parts are in the position shown in Fig. 6, will be held upon the extreme points of the sections 3 and 4 and readily removable therefrom. When removed, a reverse operation of the worm 30 10 returns the sections 3 and 4 to the position of, and plane of, operative continuity, after which a reverse operation of the shafts 13 moves the sections 1 and 2 into position between the sections 3 and 4 and the position 15 of, and plane of, operative continuity.

I claim:

1. A collapsible core comprising a plurality of segmental core sections, a support therefor, and means for movably connecting 20 one of the core sections with the support, for movement in a curved path into and out of the position of operative continuity and with relation to the plane of operative continuity.

2. A collapsible core comprising a plurality of segmental core sections, a support therefor, means for movably connecting a pair of said core sections with the support for movement in opposite directions into 30 and out of the plane of operative continuity, one of said sections being movable in an oblique direction and the other of said sections being movable in a curved path.

3. A collapsible core comprising a plurality of segmental core sections, a support therefor, means for movably connecting a pair of the core sections with the support for movement in a curved path into and out of the position of operative continuity 35 and with relation to the plane of operative continuity, and means for simultaneously moving said pair of core sections.

4. A collapsible core comprising a plurality of segmental core sections, one of said 45 sections being provided with a curved shank, a guide in which the said shank is arranged to move, and means for moving the said shank in said guide.

5. A collapsible core comprising a plurality of segmental core sections, a support 50 therefor, means to move a diametrical pair of said sections in a curved path into and out of the position of operative continuity and the plane of operative continuity, and means for moving a diametrical pair of said 55 sections in a straight path obliquely inclined to the plane of operative continuity.

6. A collapsible core comprising a plu-

rality of segmental core sections, a support therefore, means to move a diametrical pair 60 of said sections in a curved path into and out of the position of operative continuity and the plane of operative continuity, and means for moving a diametrical pair 65 of said sections in a straight path obliquely inclined to the plane of operative continuity, such movement with relation to the plane of operative continuity being in a direction opposite to that of the first pair.

7. A collapsible core comprising two pairs 70 of segmental core sections, one pair of said sections fitting between the ends of the other pair of said sections, means for moving the inner pair of the core sections in a curved path into and out of the position of operative 75 continuity and the plane of operative continuity in one direction, and means to move the other pair obliquely into and out of the position of operative continuity and the plane of operative continuity, the movement with relation to the plane of operative continuity being in a direction opposite to that of the inner pair of core sections.

8. A collapsible core comprising a centrally disposed support, bearings at or near 80 the opposite ends of said support, a pair of core sections provided with straight shanks disposed in the bearings at or near one end of the support, and a pair of core sections having curved shanks disposed in curved 85 bearings at or near the opposite end of the support, and means engaging the said shanks to impart movement thereto and to the core sections supported thereby.

9. A collapsible core comprising a central 90 support, a pair of curved bearings at or near one end of the said support, a pair of core sections provided with curved shanks fitted into the said curved bearings, a worm rack carried by said curved shanks, worms 100 engaging said racks, shafts upon which said worms are mounted extending and projecting at the forward end of the support and provided with means whereby the said shanks can be rotated.

10. A collapsible core comprising a central support, a pair of segmental core sections each provided with a curved shank, curved bearings at one end of the support receiving the curved shanks, and means engaging the said shanks and projecting at the opposite end of the support for imparting to the said shanks movement in their bearings whereby the core sections carried thereby are movable in a curved path.

PETER DE MATTIA.
